UNITED STATES PATENT OFFICE.

GILMAN JAQUITH, OF MAYSVILLE, KENTUCKY, ASSIGNOR TO HIMSELF AND JANUARY & WOOD, OF SAME PLACE.

SPINDLE-BOLSTER.

SPECIFICATION forming part of Letters Patent No. 308,167, dated November 18, 1884.

Application filed January 3, 1884. (No model.)

To all whom it may concern:

Be it known that I, GILMAN JAQUITH, of Maysville, in the county of Mason and State of Kentucky, have invented certain new and useful Improvements in Spindle-Bolsters; and I do hereby declare that the following is a full, clear, and exact description thereof, reference being had to the accompanying drawings, and to the letters of reference marked thereon, which form part of this specification.

This invention relates to bolsters for spindles such as are used in cotton-spinning machines; and it has for its object to provide a device which shall possess superior advantages in point of simplicity, durability, and general efficiency, as will be hereinafter fully described, and particularly pointed out in the claim.

In the annexed drawings, Figure 1 is a vertical sectional view of my improved spindle-bolster. Fig. 2 is a view of one side of the same. Fig. 3 is an end view of the bolster. Fig. 4 is a vertical sectional view of the spindle-bolster with its surrounding bolster-case. Fig. 5 is a perspective view of the bolster.

The same letters of reference refer to the same parts in all of the figures.

A in the drawings is the bolster, which is preferably constructed of iron, and which consists of the central cylindrical portion or waist, B, provided at or near the upper end with a tapering annular head, C, and having at its lower end an annular enlargement, D.

E designates the cylindrical bolster-case, in which the bolster is inserted. Said bolster-case is enlarged at its upper end to provide the oil-cup E', forming a receptacle into which lubricating material may be poured. The bolster-case is of such diameter interiorly that the annular enlargement D at the lower end of the bolster shall fit loosely within the same, while the tapering annular head C at the upper end of the bolster fits snugly in the bore of the bolster-case at its upper end, whereby the bolster is suspended and held from rotation. The tapering annular head C and annular enlargement D of the bolster A are provided with longitudinal grooves or passages

F, through which the oil may pass from the oil-cup E' into the reservoir or chamber G, between the bolster and bolster-case. The waist of the bolster is provided on opposite sides with longitudinal slots H, alternating as shown, through which the lubricant is admitted to the spindle, which has its side bearing in said bolster, and which, being freely lubricated, will rotate freely without tremble or jar.

By reason of the tapering annular heads at the upper end of the bolster it is unnecessary to employ a set-screw or other fastening device for securing the bolster in its case, and the bolster is self-centering. The annular enlargement D at the lower end of the bolster being of less diameter than the bore of the bolster-case admits of a certain degree of lateral motion of the bolster within the bolster-case, which enables the spindle to find a vertical center of rotation, especially inasmuch as a cushion of oil is formed between the annular enlargement D of the bolster and the surrounding wall of the bolster-case.

One of the important advantages of my invention is the omission of projecting screw-heads on the outer side of the bolster-case and openings which allow oil to leak out. Such projections catch lint and dust, which can only be removed with difficulty.

On the floor of the bolster-case A is a perforated block, J, in which is applied the stem of a step, K, on which the spindle is supported.

Having described my invention, I claim—

The combination of a bolster-case, having an oil-cup at its upper end and a step, K, at its lower end, with a bolster which is slotted longitudinally, and provided with a tapering longitudinally-grooved head at its upper end and a longitudinally-grooved enlargement at its lower end, substantially as described.

In testimony that I claim the foregoing as my own I affix my signature in presence of two witnesses.

GILMAN JAQUITH.
